Primary Examiner—Robert M. Spear(74) *Attorney, Agent, or Firm*—BakerBotts LLP**CLAIM**

The ornamental design for a tread of a tire, as shown and described.

DESCRIPTION

FIG. 1 is a perspective view of a tread of a tire of the present invention, it being understood that the pattern is repeated uniformly throughout the circumference of the tread, FIG. 2 is an elevational view of the tire tread design shown in FIG. 1,

FIG. 3 is a side view of the tire tread shown in FIG. 1, FIG. 4 is a perspective view of an alternative embodiment of the tire tread shown in FIG. 1, it being understood that the pattern is repeated uniformly throughout the circumference of the tread; and,

FIG. 5 is an elevational view of the tire of FIG. 4.

The broken lines showing the tire inner bead and sidewall in FIGS. 1, 3 and 4 are for illustrative purposes only and form no part of the claimed design.
